MEANS FOR DRILLING WELLS

Joseph P. Lawlor, Ames, Iowa

Application August 15, 1934, Serial No. 739,916

7 Claims. (Cl. 255—19)

The principal object of my invention is to provide a rotary drill for drilling wells that makes possible the rotating of the drill bit at a much higher rate of revolutions per minute than has been possible heretofore.

A still further object of this invention is to provide a well drill of the rotary type that permits the direct connecting of the prime mover to the drill shaft.

10 A still further object of my invention is to provide a means for drilling wells that insures a substantially straight hole.

A still further object of this invention is to provide a well drilling apparatus that is easily 15 operated and under the complete control of the operator at all times.

A still further object of my invention is to provide a well drilling bit that is of proper dynamic balance and one of self-centering properties.

20 A still further object of my invention is to provide a well drilling apparatus that is economical in manufacture and durable in use.

These and other objects will be apparent to those skilled in the art.

25 My invention consists in the construction, arrangement and combination of the various parts of the device, whereby the objects contemplated are attained as hereinafter more fully set forth, pointed out in my claims and illustrated in the accompanying drawings, in which:

Fig. 1 is a side view of my rotary well drill and cooperating elements in operation.

Fig. 2 is an enlarged view of the upper portion 30 of my well drill with sections cut away to more fully illustrate its interior construction.

Fig. 3 is an enlarged top plan view of the guide base table and is taken on line 3—3 of Fig. 2.

Fig. 4 is an enlarged cross-sectional view of my 35 drill bit taken on line 4—4 of Fig. 2.

Fig. 5 is an enlarged view of the worm gear mechanism for holding, lowering, and raising the drilling mechanism.

Fig. 6 is an enlarged bottom view of my rotary 40 drill bit.

45 In the present day well drilling equipment of the rotary drill type, the cutting bit usually operates at a speed ranging between sixty and one hundred twenty revolutions per minute. The power for rotating the drilling shaft and bit is transmitted from the prime mover to the shaft by a system of gears, belts, or like. Such construction and method of operation is very slow and the resulting hole is far from straight. Also, present bit heads are poorly designed, are of minimum height, and tend to cut at a tangent to the longitudinal axis of the hole being drilled. I have overcome such objections as will hereinafter be appreciated.

50 Referring to the drawings, I have used the numeral 10 to designate an ordinary derrick having a

cable wheel 11 at its top. Such a derrick or like structure is directed over the area in which the well is to be drilled. The numeral 12 designates a table base designed to be properly secured below the derrick and over the well to be dug. The 5 numerals 13 and 14 designate two detachable sections which form the central portion of the base 12, as shown in Fig. 3. The numeral 15 designates the housing of a prime mover. Any suitable type of prime mover may be used, but I recommend an 10 electric motor and in my drawings I show such a type of prime mover. The numeral 16 designates the vertical shaft of the vertical electric motor. This shaft 16 is hollow and extends a substantial distance above and below the motor proper. As 15 shown in Fig. 2, the armature of the electric motor is inside the motor housing 15 and is secured to and around the shaft 16. The numeral 17 designates an auxiliary housing secured to the top of the motor housing 15 and embracing the upper 20 portion of the shaft 16. This shaft 16 barely extends through the top of the housing 17 and is water sealed at the point of its passage through the housing 17 by packing 18 and packing retaining element 19. The numeral 20 designates 25 hand holes in the side wall of the housing 17. The numeral 21 designates a lower thrust bearing inside the housing 17 and secured to the top of the motor housing 15. The numeral 22 designates a complementary thrust bearing rigidly secured on 30 the shaft 16 and in engagement with the thrust bearing 21. The numeral 23 designates a lock nut on the shaft 16 for locking the thrust bearing 22 against accidental displacement.

The numerals 24 designates a circular plate 35 rigidly secured to the shaft 16 by being clamped between the lock nut 23 and thrust bearing 22. This plate 24 is curved downwardly and outwardly near its periphery and its use will hereinafter be appreciated. The numeral 25 designates a 40 drain pipe communicating with the inside bottom portion of the housing 17. The numeral 26 designates a water jacket housing of inverted cup construction rigidly secured to the top of the housing 17 and embracing and communicating with the inside top of the shaft 16. The numeral 27 designates an inlet pipe communicating with the inside of the housing 26. The numeral 28 designates a ball element secured to the upper portion of the housing 26. The numeral 29 designates an elongated downwardly extending guide bearing member secured by spot welding or like to the bottom of the motor housing 15. This bearing member 29 loosely embraces the shaft 16 which protrudes a short distance below its lower end. The numerals 50 30 and 31 designate diametrically opposed longitudinally extending ribs on the periphery of the bearing member 29. This bearing member 29 and ribs 30 and 31 extend into and through a complementary opening and complementary slotways in 55 60

the members 13 and 14 of the table 12, as shown in Fig. 3, during the well drilling process. The numeral 32 designates shaft sections capable of being threaded to each other and to the lower portion 5 of the shaft 16, as shown in Fig. 1. There are various methods of securing such bit shafts to each other and any suitable method may be used, provided it properly aligns the various sections and rigidly holds them together. I have used the 10 numeral 33 to generally designate my drill bit which is secured to the lowest of the shaft sections 32. The body portion of this bit is of elongated cylindrical proportion and has on its dead center bottom, a centering point 34.

15 The longitudinal central water passageway 35 of the bit has its upper end communicating with the inside of the hollow drill shafts 32 and its lower end communicating with the bottom of the bit by three outlet passageways 36 which terminate 20 at spaced apart positions around the centering point 34. The numeral 37 designates a plurality of passageways having their upper ends communicating with the top of the body of the bit and their lower ends communicating with the bottom 25 of the body of the bit. The numeral 38 designates a peripheral row of cutting teeth on the bottom of the drill bit. The numeral 39 designates cutting blades on the bottom of the drill bit extending outwardly from the centering point 34, as 30 shown in Fig. 6. The numeral 40 designates a water pump shown in conventional form and operated by a motor 41 also shown in conventional form. The numeral 42 designates the outlet pipe of the pump 40. Such water pumping apparatuses are universally used in the drilling of wells and I use the same system, i. e., forcing water down to the bottom of the hole being drilled, permitting it to flow upwardly around the drill shaft and out through a drain or like 43 at 40 the top of the well, carrying with it the material cut loose by the bit at the bottom of the hole. The numeral 44 designates a flexible hose having one end connected to the pipe 27 and its other end to the pipe 42. The numeral 45 designates a rotatably mounted drum having a shaft 46. The numeral 47 designates a worm gear on the shaft 46. The numeral 48 designates a rotatably mounted shaft capable of being rotated in either direction by the hand crank 49. The numeral 50 50 designates a small worm gear on the shaft 48 and in engagement with the worm gear 47. The numeral 51 designates a cable having one end secured to the drum 45, its central portion embracing the cable wheel 11, and its other end secured 55 to the bail 28. The numeral 52 designates a well hole in the earth 53. The numeral 54 designates an oil cup for furnishing oil to the device.

The practical operation of the device is as follows: The prime mover, supported parts, drill shaft, and drill bit are manually lowered by the crank 49 until the drill bit is in suitable engagement with the earth. With the prime mover running, the drill bit will naturally drill and cut into the earth and will continue to move downwardly 60 in the well hole it cuts by periodical adjustment of the cable 51 by the crank arm 49. This downward movement of the drill bit will continue until the housing 15 of the prime mover reaches the plate base 12, at which time it will be necessary to 65 reverse the rotation of the crank arm 49 and raise the prime mover, bearing element 29, drill shaft, and drill to an elevated position where the lower end of the bearing 29 and lower end of the shaft 16 will be above the plate 12. With the 70 motor stopped, the drill shaft will be unscrewed 75

from the lower end of the shaft 16 and another drill shaft section 32 added to the drill shaft, after which the now increased length of drill shaft will be threaded onto the lower end of the shaft 16. The apparatus is then again manually lowered to a point where the lower end portion of the bearing member 29 extends through the opening in the plates 13 and 14 and the drill bit is again in proper engagement with the bottom of the hole. The motor is then again turned on and drilling operations resumed. This procedure is repeated until the well has been drilled the desired depth. The length of the bearing member 29 will be substantially the depth a hole can be sunk before it becomes necessary to again elevate the apparatus and interpose another section in the drill shaft. The apparatus should be lowered by the adjustment of the cable 51 as rapidly as the bit will efficiently cut and the prime mover can successfully rotate the same. 20

The operator may easily and quickly determine the proper manual adjustment of the cable and the lowering of the apparatus by watching the power load of the prime mover. Any suitable instrument may be used to gauge this and in Fig. 21 I show a gauge 55 interposed in the electric lead wires 56 of the prime mover. By observing this gauge an operator may operate the crank arm 49 to the right or to the left to obtain the proper contact of the lower end of the drill bit with the 25 formation being drilled. The ribs 30 and 31 slidably engage the plates 13 and 14 respectively, thereby preventing the rotation of the prime mover housing and bearing member 29.

My method of getting water to the bottom of the hole is an important phase in the construction of my apparatus. The water from the pump 40 is forced through the flexible hose 44 into the housing 26. The flexible hose 44 permits the lowering and raising of the prime mover as hereinbefore described. From the housing 26 the water under pressure passes downwardly through the prime mover shaft 16 and into the hollow drill shaft. From the drill shaft the water passes into the bit and from the bit through the outlet 45 openings 36. This water absorbs and/or carries upwardly the material loosened by the bit through the passageways 37 and into the drill hole around the shaft 32 from which it passes out of the top of the well in the usual manner. By passing the 50 water through the prime mover shaft a desirable water connection can be obtained and the motor kept in a relatively cool condition during its operation. If any water should leak through and around the packing material 18 it will drop onto the plate 24, which rotates with the shaft 16. The rotation of this plate 24 will, by centrifugal force, cast this undesirable water to the sides of the housing 17, thereby preventing the same from 55 getting into the inside of the prime mover housing and damaging the motor. 60

As a further precaution against any water getting into the motor housing the outer peripheral edge of the plate 24 is bent downwardly and outwardly to loosely embrace an upwardly extending 65 cup portion 57 on the bearing member 21, as shown in Fig. 2. The water collected in the housing 27 eventually passes from the same through the drain pipe 25.

From the foregoing it will be seen that the 70 prime mover, its supported elements, the bearing guideway 29, drill shaft, and bit will be freely floating inasmuch as they are suspended by cable from the top of the derrick. This phase of the apparatus is very important and promotes not 75

only the rapid drilling of a hole, but a hole that is straight. As the device is at all times under the control of the operator it will be unnecessary for any excessive strain to be put on either the 5 motor, drill bit, or drill shaft. The drill shaft will at all times be kept in proper alignment with the hole being dug by virtue of the bearing guide member 29, which in turn will be held in proper 10 position at all times by the cable 51 and contact with the table base. The true and straight cutting of the drill bit is encouraged by its novel construction and design. By making the body portion of the drill bit of substantial height as 15 shown in Fig. 1, it will have a tendency to conform with the hole being drilled and to be held thereby in a straight position. The point 34 and peripheral teeth 38 also aid in causing the drill bit to cut true and straight. By a substantial portion 20 of the entire drilling apparatus being suspended from the top of the derrick, not only will it be possible to obtain a substantially straight hole, but the drill bit may be successfully rotated at a speed of several hundred revolutions per minute. As shown in the drawings, the speed of 25 rotation of the drill bit will be the same as that of a prime mover.

Some changes may be made in the construction and arrangement of my improved means for 30 drilling wells without departing from the real spirit and purpose of my invention, and it is my intention to cover by my claims any modified forms of structure or use of mechanical equivalents which may be reasonably included within 35 their scope.

I claim:

1. In a device of the class described, a base plate having an opening, a vertical guide bearing member slidably mounted in the opening of said base plate, a prime mover secured to the upper 40 end of said bearing member having a motor shaft extending downwardly and through said bearing member, a drill shaft detachably secured to the lower end portion of said motor shaft, a drill bit on said drill shaft, and a means for regulating 45 the sliding movement of said guide bearing member.

2. In a device of the class described, a base plate having an opening, a vertical guide bearing member slidably mounted in the opening of said base plate, notches in said base plate and adjacent said opening therein, vertical rib members on said guide bearing member slidably engaging said notches in said base plate respectively, a prime mover secured to the upper end of 50 said bearing member having a motor shaft extending downwardly and through said bearing member, a drill shaft detachably secured to the lower end portion of said motor shaft, a drill bit on said drill shaft, and a means for vertically 55 sliding said guide bearing member in the opening of said base plate.

3. In a well drilling apparatus of the rotary type, a prime mover having a hollow vertical motor shaft, a hollow drill shaft operatively connected to said motor shaft and communicating with the inside of the same, a housing loosely embracing one end portion of said motor shaft, thrust bearings inside said housing and embracing said motor shaft, a plate rigidly secured 60 on said motor shaft inside said housing and above said thrust bearings, a second housing designed to be in communication with a source of fluid 65

under pressure and communicating with the inside of said motor shaft, and a material agitating element on said drill shaft.

4. In a device of the class described, a base member having an opening, a vertical guide bearing member slidably mounted in the opening of said base plate, a means for preventing the independent rotation of said vertical guide bearing member relative to said base plate, a shaft extending downwardly and through said bearing 10 member, a prime mover secured to the upper end of said bearing member and operatively secured to said shaft, a drill shaft detachably secured to the lower end portion of said shaft, a material agitating element on said drill shaft, and a means 15 for vertically sliding said guide bearing member in the opening of said base plate.

5. In a well drilling apparatus of the rotary type, a prime mover having a hollow vertical motor shaft, a hollow drill shaft operatively connected to said motor shaft and communicating with the inside of the same, a material agitating element on said drill shaft, a housing loosely embracing the upper end portion of said motor shaft at a point slightly below the upper end of the 25 motor shaft and above said prime mover, thrust bearings inside said housing embracing said motor shaft, a horizontal plate rigidly secured on said motor shaft inside said housing and above said thrust bearings, a conduit element designed 30 to be in communication with a source of fluid under pressure communicating with the inside top of said motor shaft, and a fluid draining means communicating with the inside of said housing at a point below said plate. 35

6. In a well drilling apparatus of the rotary type, a prime mover having a hollow vertical motor shaft, a hollow drill shaft operatively connected to said motor shaft and communicating with the inside of the same, a material agitating 40 element on said drill shaft, a housing loosely embracing the upper end portion of said motor shaft at a point slightly below the upper end of the motor shaft and above said prime mover, thrust bearings inside said housing embracing 45 said motor shaft, a horizontal plate rigidly secured on said motor shaft inside said housing and above said thrust bearings, a vertical screening collar for said thrust bearings inside said housing and extending upwardly to a point just below said 50 plate, a conduit element designed to be in communication with a source of fluid under pressure communicating with the inside top of said motor shaft, and a fluid draining means communicating with the inside of said housing at a point below 55 said plate.

7. In a well drilling apparatus of the rotary type, a prime mover having a hollow vertical motor shaft, a hollow drill shaft operatively connected to said motor shaft and communicating 60 with the inside of the same, a housing loosely embracing one end portion of said motor shaft, thrust bearings inside said housing and embracing said motor shaft, a plate having its marginal edge bent downwardly rigidly secured on said 65 motor shaft inside said housing and above said thrust bearings, a second housing designed to be in communication with a source of fluid under pressure and communicating with the inside of said motor shaft, and a material agitating element on said drill shaft. 70

JOSEPH P. LAWLOR.
